UNITED STATES PATENT OFFICE

JOHN REICHERT, OF RACINE, WISCONSIN

HAT-DISPLAY RACK

Application filed September 12, 1928. Serial No. 305,524.

This invention relates to certain improvements in hat display racks; and the nature and objects of the invention will be readily recognized and understood by those skilled in the art in the light of the following explanation and detailed description of the accompanying drawings illustrating what I at present consider and believe to be the preferred embodiments or mechanical expressions of my invention from among various other forms, arrangements, combinations and constructions of which the invention is capable within the spirit and the scope thereof.

The racks with which the invention is primarily and mainly concerned, are those of the so-called "tree" types employed for displaying hats and such like articles in stores, show rooms, and other places of display, although the invention is not restricted to such types of racks, or to the objects and articles which it may be desired to mount and display thereon. With such racks among the important considerations are the floor and room space occupied by a rack in use, the number of articles which the rack will hold and efficiently display, and the appearance of the rack.

A general object of the invention, is, therefore, to provide a rack which is so designed and arranged as to occupy a minimum of floor and room space, yet which will enable a relatively large number of articles to be mounted thereon and efficiently displayed thereby without obstruction by structure of the rack or interference between and obstruction by adjacent articles being displayed on the rack, and further to provide such a rack which will present a pleasing and attractive appearance in use.

Another object of the invention is to provide a rack of the so-called "tree" type, which is constructed of metal, and so designed as to permit of the utilization of standard or stock metal materials with a minimum of special parts and fittings, to thereby secure a rack design and construction of strength and durability, but of relatively simple construction, easily manufactured and of comparatively low cost.

Another object of the invention is the pro-

vision of an improved design and construction of supporting base for a rack, by which great strength and rigidity are obtained, with the strong, rigid mounting and anchoring of the rack structure on and to the base made possible.

A further object of the invention is to provide a mechanically simple but efficient design of hat supporting arm and mounting therefor on the rack standard or mast, so that such arms are mounted in vertically staggered relation to enable the use of a maximum number of such supports for a given mast or standard length without interference therebetween.

Another object of the invention is to provide a rack design and construction such that the rack can be readily and quickly assembled or set-up for use, and can be quickly disassembled for shipment or storage.

With the foregoing general objects, and certain other objects and results in view which will be readily recognized from the following explanation, the invention consists in certain novel features in construction and in combinations and arrangements of parts, as will be fully and particularly referred to and specified hereinafter.

Referring to the accompanying drawings, in which similar reference characters refer to corresponding parts throughout the several figures thereof:

Fig. 1, is a view in side elevation of a hat display rack embodying the several features of the invention.

Fig. 2, is a view in horizontal section through the rack mast taken on line 2—2, of Fig. 1, and showing the supporting base and a supporting arm unit in top plan.

Fig. 3, is a horizontal section through the rack mast taken on the line 3—3, of Fig. 1.

Fig. 4, is an enlarged detail transverse section through the rack mast showing the hub of a supporting arm unit in top plan and the mounting of the supporting arms thereon.

Fig. 5, is a view in side elevation of a supporting arm unit and hub in mounted position on the rack mast.

Fig. 6, is a vertical section taken on the line 6—6, of Fig. 4.

Fig. 7, is a vertical section through the base and mast mounting thereon, taken on the line 7—7, of Fig. 3.

Fig. 8, is a vertical section similar to Fig. 7, but taken at right angles thereto, on the line 8—8, of Fig. 7.

The form and embodiment of hat display rack of the invention disclosed in the accompanying drawings by way of an example to present the several features of the invention, 10 is of the so-called "tree" type, and includes the supporting base structure 10 having the vertical standard or mast 20 fixed thereon and carrying the series of hat supporting and displaying members or arms 30 mounted in vertically spaced relation extending radially therefrom.

The supporting base structure 10 includes the channel bars 11 and 12, each centrally arched and terminating at its opposite ends in the feet 14. These foot forming bars 11 and 12 of the base 10 are disposed in crossed relation, in the present instance at substantially right angles to each other, with their 20 channels facing and opening upwardly, and with the bar 12 mounted extending over and across the bar 11. A foot forming bar securing and mast carrying member 15 is provided for mounting on and across the crossed 25 intermediate sections of bars 11 and 12, to secure and maintain these foot forming bars in rigid fixed relation and position. In the 30 particular form of the member 15 as here shown, it comprises the central upwardly 35 extended mast receiving socket portion 16, with the depending central boss or lug 17 (see Figs. 7 and 8) fitting down into and engaging the channel of the upper channel bar 12. A 40 suitable securing member, such as the machine screw 18, is extended upwardly through the crossed channel bars 11 and 12, below and in line with the central depending boss or lug 17, and is threaded upwardly into such lug 45 17, to tightly bind and secure the bars 11 and 12 together clamped between screw 18 and member 15.

The member 15 is provided and formed with the diametrically opposite pairs of radially extending and depending fingers 19 and 19', respectively. The opposite aligned fingers 19 are of greater length and depend below fingers 19', for engaging and fitting into the channel of bar 11, while the shorter, opposite and aligned fingers 19' fit into and 50 engage the channel of the upper bar 12, as will be clear by reference to Figs. 7 and 8 of the drawings in particular. By this construction and arrangement, the fingers 19 and 19' engaging and fitting into the channels 55 of bars 11 and 12, respectively, rigidly secure and lock these foot forming bars in position against lateral or twisting movements relative to each other, or around securing member 18 as an axis, such rigid locking being aided by the depending central 60

boss or lug 17 which fits between and engages the opposite side walls of the channel on the upper side of bar 12. The bars 11 and 12 are securely clamped and held against separating movements by the member 15 and the screw 18, so that, a rigid, strong supporting base structure results of simple, inexpensive construction, capable of being assembled and disassembled by applying and removing the single fastening or securing element or screw 18. While the invention is not so limited, it is preferred to utilize standard or stock materials and sizes of channel irons or bars in forming the bars 11 and 12 of the base structure 10, such standard or stock channel bars being readily obtainable and comparatively inexpensive.

The base structure 10 described above supports and mounts the rack structure which includes the vertical standard or mast 20. In the example hereof mast 20 is formed of a length of suitable metal tubing, such as the readily obtainable standard metal gas piping or the like of relatively low cost. The standard or mast 20 is externally threaded at one end to form a screw fit with the internally threaded socket member 16 of the bar securing member 15 of base structure 10, and is secured in such socket member 16 extending vertically from and disposed centrally or axially of the base structure. The upper end of mast 20 is preferably provided with any suitable decorative element, such as the ball member 21 shown in Fig. 1, and slotted to receive and hold any suitable legend bearing plate or card 22. The mounting of the standard or mast 20 is clearly shown by Figs. 7 and 8 of the drawings taken in connection with Fig. 1.

A series of hat supporting and displaying members or arms 30 are mounted in vertically spaced units or clusters on mast 20. Each arm unit or cluster comprises a hub member 31 adjustably secured to the standard 20 by set screws or the like 32, referring now to Figs. 4, 5 and 6 of the drawings, and the pairs of diametrically opposite arms 30. The hubs 31 are each formed with the pairs of diametrically opposite vertical ribs or radial projections 33 disposed longitudinally thereof, and terminating at their upper outer sides in the vertically disposed spaced lugs or fingers 34, respectively. Spaced inwardly from each of the pairs of lugs or fingers 34 and disposed on a line intermediate such lugs, the hub 31 is formed with a vertical bore 35 therethrough, as shown particularly by Fig. 6 of the drawings. The series of hubs 31, so formed, are mounted at spaced intervals along standard or mast 20, at the desired distances apart to secure the required spacing and clearance between hat supporting arms 30, with the hubs so arranged that the ribs or projections 34 thereof are disposed intermediate 105 110 115 120 125 130

or staggered with the ribs 34 of adjacent hubs, respectively, as shown in Fig. 1.

The hat displaying and supporting arms 30 each comprise, or are formed, in the specific 5 instance here shown, of a length of wire, rod, or the like material, bent or otherwise formed, to provide the vertical or depending end 36 (see Fig. 6), the horizontally disposed arm 37, and the upwardly extending vertically disposed portion or leg 38 terminating in the laterally extended, horizontally disposed loop 39, forming a hat receiving and supporting seat or base. A hat displaying and supporting arm 30 is mounted in position on a hub member 31, with the depending end 36 fitted and received down into a hub bore 35, and the arm portion 37 disposed between the adjacent pair of fingers 34 and extending outwardly and radially from the hub. The 15 fingers 34 maintain the arm against lateral movement and the depending end 36 in hub bore 35 retains the arm member 30 in mounted position against displacement, but permits of the ready removal of an arm member from 20 the hub when desired.

The series of vertically spaced hubs 31 relatively arranged on the rack standard or mast 20 as described, each supports and mounts four of the hat displaying arm members 30 in the example hereof, although the invention is not limited to any particular number, as it will readily appear that any desired number can be employed by merely providing the required number of hub bores 35 and spaced fingers 34 to mount the arm members. The arm members 30 in the rack here illustrated are mounted on each hub 31, the arm members 30 of each hub 31 are staggered or lie disposed between or intermediate the arms of the adjacent hub members, respectively, as shown clearly by Fig. 1 of the drawings. In this manner, interference between arm members 30 and the hats supported and displayed thereon is eliminated, and it is possible to display a maximum number of articles for a given rack mast 50 length, in an efficient manner.

The metal rack of the form illustrated and described as an example of the invention, is of pleasing and attractive appearance, mechanically and structurally simple and relatively inexpensive to manufacture, yet presents a rack which occupies a minimum of floor and room space while permitting of the display in an efficient manner of a relatively large number of hats or other articles. The 55 arrangement and construction of the supporting base structure 10 insures great strength and rigidity against torsional or twisting strains, without great weight or large and space occupying structure. The compactness of the arrangement of mast carried support-

ing and display arms 30 materially aids in the location of the weight along and in proximity to the vertical axis of the entire rack structure, which together with the rigid base structure and the arrangement thereof by which forces are evenly distributed thereto, permits of the application of relatively large lateral forces to the rack with minimum possibility of upsetting or displacing the rack from upright position.

It is also evident that various changes, modifications, variations, substitutions, and eliminations might be resorted to without departing from the spirit and scope of my invention, and hence I do not desire to limit myself to the exact and specific disclosures hereof.

What I claim, is:

1. In a rack, a base structure including, crossed foot forming channel bars having the channels on their upper sides, a member securing said bars together at their point of crossing, and said member engaged and fitting into the channels of said bars, respectively, at opposite sides thereof to maintain the bars against lateral movement.

2. In a rack, a base structure comprising, crossed foot forming bars, a member clamping said bars together at their point of crossing, said bars formed with depressions on their upper sides adjacent and at opposite sides of said member, and means carried by said member engaging the upper side depressions in said bars at opposite sides of the member to maintain the bars against lateral movement.

3. In a rack, a supporting base comprising crossed foot forming channel bars having the channels on their upper sides, a member fitting over said bars at their point of crossing, a securing member extending upwardly through the crossed bars and secured to said member to clamp the bars and member together, and projections on said member fitting into the channels of said bars to maintain the bars against relative lateral movement.

4. In a rack, a base structure comprising, centrally arched channel bars having their opposite ends providing supporting feet, said bars crossed at their centrally arched portions with one bar extended over and across the other and having their channels disposed upwardly, a clamping and securing member mounted over the crossed central portions of the bars and fitting into the channel of the upper bar at the point of crossing with the bar therebelow, a securing screw extending upwardly through the crossed bars into and engaging the said member to clamp the bars together, and said member formed with pairs of opposite radial projections depending therefrom engaging and fitting into the channels of said bars, respectively, to maintain the bars against lateral movement.

5. In a rack, a supporting base structure

including crossed foot forming bars, a securing and clamping member mounted over said bars at their point of crossing, lateral projections on said member above and in vertical alinement with said bars, respectively, at opposite sides of the member, and said projections engaging the bars to maintain the same against relative lateral movements.

5 6. In a rack, a vertical standard, a hub member thereon, said hub member formed with vertical bores therethrough, spaced vertical projections on its upper side spaced outwardly from each bore, respectively, and article displaying arms each formed with a horizontally disposed portion having a depending end, said arms mounted on the hub with the depending ends in said bores and the horizontally disposed portions between the adjacent spaced projections, respectively.

10 7. In a rack including a vertical standard, a hub member on said standard having a vertical bore opening through the upper side thereof, spaced vertical projections from the upper side of said hub member spaced outwardly from the bore with the latter disposed on a line intermediate the projections, and an article displaying arm formed of a length of wire material to provide a horizontal portion terminating at one end in a depending vertical portion and at the opposite end in an upwardly extending article receiving and supporting portion, said arm mounted on the hub member with the depending end portion fitted in the vertical hub bore and the horizontal portion extending outwardly from the hub and disposed between said spaced projections.

15 8. A supporting base structure comprising, crossed foot-forming bars, a clamping member mounted on said bars over their point of crossing, a fastening member extending through said bars at their point of crossing and connected to said clamping member to fasten and secure the crossed bars together, and projections on said clamping member above each bar in the vertical plane thereof and engaging each bar at opposite sides of the clamping member to maintain the bars in position against relative lateral movements.

20 9. A supporting base structure comprising, crossed foot forming bars, a member mounted over and clamping said bars together at their point of crossing, and projections from said member engaging each bar at opposite sides of and spaced from the point of crossing of the bars to maintain the crossed bars in position against relative lateral movements.

25 Signed at Racine, county of Racine, State of Wisconsin, this 10th day of September, 1928.

JOHN REICHERT.
